George W. Kelley, Philadelphia, Pa.

Application August 9, 1943, Serial No. 110,872

Term of patent 7 years

To all whom it may concern:

Be it known that I, George W. Kelley, a citizen of the United States, residing at Philadelphia, in the county of Philadelphia and State of Pennsylvania, have invented a new, original and ornamental, Design for a Combined Butter Dish and Knife Rest, or Similar Article, of which the following is a specification, reference being had to the accompanying drawing, forming a part thereof.

Figure 1 is a top plan view of a combined butter dish and knife rest, or similar article, showing my new design;

I claim:

The ornamental design for a combined butter dish and knife rest, or similar article, as shown.

GEORGE W. KELLEY.
